UNITED STATES PATENT OFFICE

CLARENCE E. SPICER, OF TITUSVILLE, PENNSYLVANIA, ASSIGNOR OF THREE-FOURTHS TO LUTHER B. PRESTON, OF STEUBEN, PENNSYLVANIA.

DESIGN FOR A WHEEL-SPOKE.

SPECIFICATION forming part of Design No. 31,447, dated August 22, 1899.

Application filed July 29, 1899. Serial No. 725,539. Term of patent 14 years.

To all whom it may concern:

Be it known that I, CLARENCE E. SPICER, a citizen of the United States, residing at Titusville, in the county of Crawford and State of Pennsylvania, have invented and produced a new and original Design for a Wheel-Spoke, of which the following is a specification, reference being had to the accompanying drawings, forming part thereof, and in which—

10 Figure 1 is a side view, and Fig. 2 an edge view, of a spoke, showing my new design.

The leading or material feature of my design consists of the subject-matter of the accompanying illustrations.

15 The body A of the spoke is threaded at its inner end B and is provided near its said threads with a non-circular portion C. The

spoke gradually reduces in diameter toward its outer end and is provided at its said end with the flattened tines or arms D and with 20 the prong E, lying between the said arms. As shown in Fig. 1, the tines present considerable width in side view and gradually taper at D' to their juncture with the body of the spoke. 25

Having described my invention, what I claim as new, and desire to secure by Letters Patent, is—

The design for a wheel-spoke as herein shown and described.

CLARENCE E. SPICER.
